UNITED STATES PATENT OFFICE.

GILES VALENTINE SULLIVAN, OF SAN FRANCISCO, CALIFORNIA, ASSIGNOR TO BETHLEHEM SHIPBUILDING CORPORATION, LTD., OF SOUTH BETHLEHEM, PENNSYLVANIA, A CORPORATION OF DELAWARE.

HYDRAULIC PRESS FOR TURBINE-WHEELS.

1,307,764.

Specification of Letters Patent. Patented June 24, 1919.

Application filed November 8, 1918. Serial No. 261,625.

To all whom it may concern:

Be it known that I, GILES VALENTINE SULLIVAN, a citizen of the United States, residing in the city and county of San Francisco, State of California, have invented a new and useful Hydraulic Press for Turbine-Wheels, of which the following is a specification.

In the art of assembling turbine wheels of the type usually used for the propulsion of marine vessels with respect to their shafts, and wherein the latter are forcibly pressed into said wheels as by hydraulic pressure, it is essential that said shaft be forced into said turbine wheel in a uniform and expeditious manner, and it is also essential that the hydraulic ram be expeditiously returned to its initial or normal position. In order that this operation may be facilitated and carried on with a minimum of labor and expense, I have devised a novel construction and collocation of a hydraulic cylinder and ram mounted on a laterally extending upper frame work, in conjunction with a lower supporting frame for the wheel and shaft, during the operation of pressing the latter into the former, both of said frames being braced and stayed or tied together in a novel manner, so that the upper frame work properly takes up the thrust of the ram, when it is applied to the shaft which is to be forced into the turbine wheel. In performing operations of this character, the pressure exerted is frequently very high and it is essential that the connections between the upper frame supporting the ram and the lower frame or bed supporting the turbine wheel and shaft, during the assembling operations, be very rigid and further that provision be made for effecting a slight up and down adjustment of the outer ends of said frames when desired or necessary, so that the vertical axial line of movement of the ram may always be coincident with the axial vertical downward line of movement of the shaft with respect to the turbine wheel and to provide for such adjustment, I employ a tie rod passing through the upper and lower frames and having adjusting devices collocated thereon above and below the outer ends of the upper and lower frames.

To the above ends, I mount said upper and lower frames upon a rigid upright and tie them together at their outer ends, by a

tie rod, having upper and lower adjusting devices, with respect to the outer end of each frame, provision being made for effecting the automatic return or elevation of the ram by means of counterweights carried by connections passing over sheaves mounted in bearings in the upper frame work, one end of said connections being secured to a yoke attached to the head of the ram, and the other ends of said connections carrying said counterweights.

For the purpose of illustrating my invention, I have shown in the accompanying drawings certain forms thereof which are at present preferred by me, since the same will give in practice satisfactory and reliable results. It is to be understood, however, that the various instrumentalities of which my invention consists can be variously arranged and organized and that my invention is not limited to the precise arrangement and organization of these instrumentalities as herein shown and described.

Figure 1 represents a side elevation of a hydraulic press for turbine wheels embodying my invention.

Fig. 2 represents a top plan view of Fig. 1.

Fig. 3 represents a top plan view of Fig. 1, with the sheaves and ropes removed, and

Fig. 4 represents a section on line 4—4 of Fig. 1, showing the construction of the lower frame or bed.

In carrying out my invention I employ an angular supporting upright or standard 1, the base 2 of which may be bolted or secured to a foundation. At the upper portion of said upright, I secure an upper laterally extending frame 3, comprising a plurality of plates 3^x provided at their left-hand ends with flanges or feet 4, which are secured by bolts or other fastening devices 5 to the upper portion of the upright flange 6 of the standard 1. The central portions of the upper laterally extending frame 3 are bulged outwardly to form the curved clamping members 7, which are held together by means of the bolts 8, it being apparent that the tightening of said bolts 8 clamps in position the hydraulic cylinder 9, within which the ram 10 is contained and reciprocates.

The outer ends of the pair of plates 3^x are secured in assembled position by means of the outer or right-hand bolts or other fastening devices 12, said plates 3^x being spaced

apart by means of the distance pieces 11 surrounding the bolts 8 and 12, and at their outer ends the extension 13 of the bracket 14 may enter as seen in Fig. 2, said bracket being provided with arms 14, in which the sheave 15 is rotatably mounted. The outer ends of the plates 3^x rest upon a washer or the flange 16 of the nut 17, which is mounted or threaded upon the tie rod 18, whose upper end passes between the plates 3^x and is threaded for engagement with the upper nuts 19. The lower end of said tie rod 18 is also threaded and engages the bottom nut 19, which rests upon a foundation or base, as will be evident from Fig. 1.

The lower laterally extending frame 20, which constitutes a bed for supporting the turbine wheel and its shaft, is constructed in substantially the same way as the upper lateral frame 3, as will be understood from Fig. 4, and its outer end is supported between the nuts 21 and 22, which are securely locked in position by the lock nuts 23.

24 designates a sheave mounted on the top 25 of the frame 3, in a bracket 24^x, and 25 and 26 designate sheaves mounted respectively in brackets 27 and 28 secured respectively to the top of the upper frame 3 and to the upper left-hand portion of the upright 1.

30 29 designates a yoke attached in any manner to the ram 10 and having attached to one end thereof, a wire rope or the like 30, which passes over the sheaves 24 and 15 and carries at its outer extremity a counterbalance 31.

32 designates a wire rope or the like attached to the opposite end of the yoke 29 and passing over the sheaves 25 and 26 and carrying at its outer end the weight or 40 counterbalance 33.

34 designates a turbine wheel shaft, and 35 designates a turbine wheel, the hub 36 of the latter resting upon the top of the lower frame or bed 20, which it will be understood 45 has a central aperture 37 so as to permit the shaft 34 to enter and pass therethrough, when it is pressed into the turbine wheel.

The operation is as follows:—

The turbine wheel 35 having been placed 50 in position upon the lower supporting frame or bed 20 and its shaft 34 having been placed thereupon, and the requisite hydraulic or other pressure having been created in the hydraulic cylinder 9 in the usual manner, the 55 ram 10, yoke 29 and the connections 30 and 32 move or are pressed or forced downwardly until the shaft 34 has been pressed into the turbine wheel 35 to the desired extent, as will be understood from Fig. 1.

60 Upon releasing the pressure from the hydraulic cylinder 9, the weight of the counterbalances 31 and 33 will cause the yoke and the ram 10 at once to move upwardly into substantially the position seen in Fig. 1, 65 whereupon the shaft 34 and turbine wheel

35 can be removed and another shaft and turbine wheel placed in position.

In case it is desired to adjust the ram cylinder 9 vertically, it can be done upon loosening the bolts 8, and in case the outer ends of the upper frame 3 or the lower frame or bed 20 sag from any reason, the same can be vertically adjusted to the desired extent by the proper manipulation of the nuts 17, 19 and 21, 22 and 23, upon the rod 18. The upper frame 3 takes the thrust of the ram, when it is applied to the shaft 34, which is to be pressed into the turbine wheel 35, and the lower frame or bed 20 forms a strong and convenient construction for the support of the turbine wheel and shaft during the assembling operation, and any slight adjustment of the outer ends of the frames 3 and 20, can be simultaneously effected by turning the lower nut 19, as is evident.

I have deemed it unnecessary to describe in detail the operation of the hydraulic ram employed, as any conventional type thereof may be used, the fluid pressure being conducted thereto through the liquid conduit 38.

While I have devised my invention primarily for expeditiously pressing shafts into turbine wheels, it will be apparent that I may utilize the same for forcing mandrels, 95 shafts and the like into and out of other hollow objects, as wheels, pulleys and the like, my device being obviously adapted for a wide range of work, and being capable of being shipped in sections or in a knocked-down condition, and being readily set up by unskilled labor.

I am aware of the patent to Austin, No. 1,196,504, but my invention is differentiated therefrom by the provision of the adjusting 105 devices for the outer ends of the frames 3 and 20, and in the construction of said frames and the manner of mounting and locating the latter.

It will now be apparent that I have devised a novel and useful hydraulic press for turbine wheels, which embodies the features of advantage enumerated as desirable in the statement of the invention and the above description, and while I have, in the present 115 instance, shown and described a preferred embodiment thereof which will give in practice satisfactory and reliable results, it is to be understood that the same is susceptible of modification in various particulars without departing from the spirit or scope of the claims or sacrificing any of its advantages.

Having thus described my invention, what I claim as new and desire to secure by Letters Patent, is:—

1. In a hydraulic press for turbine wheels and the like, an upright, an upper laterally extending ram supporting frame composed of a pair of plates having flanges secured to 130

- said upright, a plurality of bolts extending through said plates, the intermediate portions of the latter being bowed outwardly to form a clamping device for a ram cylinder, 5 a ram cylinder and ram supported between said plates, a lower laterally extending frame, composed of a pair of plates having flanges secured to the lower portion of said upright, a tie rod passing between the outer 10 ends of said upper and lower frames, and nuts on said tie rod above and below said frames for effecting the adjustment of the latter.
2. In a hydraulic press for turbine wheels 15 and the like, an upright, an upper laterally extending ram supporting frame composed of a pair of plates having flanges secured to said upright, a plurality of bolts extending through said plates, the intermediate portions of the latter being bowed outwardly to 20 form a clamping device for a ram cylinder, a ram cylinder and ram supported between said plates, a lower laterally extending frame, composed of a pair of plates having flanges secured to the lower portion of said upright, a tie rod passing between the outer 25 ends of said upper and lower frames, and nuts on said tie rods above and below said frames for effecting the adjustment of the latter, in combination with means for effecting 30 the automatic return of said ram.
3. In a hydraulic press for turbine wheels and the like, an upright, an upper laterally extending ram supporting frame composed 35 of a pair of plates having flanges secured to said upright, a plurality of bolts extending through said plates, the intermediate portions of the latter being bowed outwardly to form a clamping device for a ram cylinder, 40 a ram cylinder and ram supported between said plates, a lower laterally extending frame, composed of a pair of plates having flanges secured to the lower portion of said upright, a tie rod passing between the 45 outer ends of said upper and lower frames, and nuts on said tie rods above and below
- said frames for effecting the adjustment of the latter, in combination with a yoke attached to said ram, sheaves mounted above said upper frame, connections having one 50 end attached to said yoke, and passing over said sheaves, and weights attached to the outer ends of said connections.
4. In a hydraulic press for turbine wheels and the like, an upright, an upper laterally 55 extending ram supporting frame composed of a pair of plates having flanges secured to said upright, a plurality of bolts extending through said plates, distance pieces between said plates and surrounding said bolts, the intermediate portions of said plates being bowed outwardly to form a clamping device for a ram cylinder, a ram cylinder and ram supported between said plates, a lower laterally extending frame, composed of a 60 pair of plates having flanges secured to the lower portion of said upright, a tie rod passing between the outer ends of said upper and lower frames, nuts on said tie rod above and below said frames, for effecting the ad- 65 justment of the latter, a bottom nut in which the lower end of said tie rod rests, a yoke attached to said ram, sheaves mounted above said upper frame, connections having one end attached to said yoke and passing over 70 said sheaves, and counterweights attached to the outer ends of said connections.
5. In a hydraulic press for turbine wheels and the like, an upright, upper and lower laterally extending frames secured thereto, 80 the upper of said frames being formed of plates bowed intermediately of their ends, a ram cylinder secured between said plates, a tie rod passing through the outer ends of said frames, and means on said tie rod for 85 adjusting the outer ends of said frames up or down, according to requirements.

GILES VALINTINE SULLIVAN.
